ANTIARCH INTAKE

Neil H. Gebhardt, Erie, Pa.

Application April 26, 1949, Serial No. 89,729

13 Claims. (Cl. 302—39)

1 This invention relates to apparatus for transporting material by a conveying fluid current and has for its principal object the provision of means whereby the material will be prevented from forming arches, plugs, or blocks of such size as to interfere seriously with the flow of the conveying current. While the device in its narrow form is primarily intended to convey ashes from a furnace to a receiving receptacle, the fluid being air, the invention is obviously greater in scope and contemplates the feeding of any material that might arch or pile up by means of a current which could either be a gas or a liquid.

In pneumatic ash removers considerable difficulty has been had by the fine ashes building arches or other obstructions which increase in size to such an extent as sometimes to block transfer of the ashes. The present invention avoids this difficulty by having a reasonably wide conduit, either closed or not, and admitting the ashes, solid particles, or other finely divided material into the flowing stream partly on one lateral side of the conduit and partly on the other lateral side, the result being that the fluid current instead of flowing parallel to the sides of the conduit or pipe flows in a sinuous curve first around the initial admission and then around the second admission, the points of entry being spaced laterally and to a much greater extent longitudinally. Consequently when the particles in the initial entry start to form an arch the arch or a packed mass is eroded by the action of the fluid stream which is now moving toward the side from which the particles are being admitted. As the stream passes the second point of entry it will again break the arch, this time pulling the base of the arch or blocked mass toward the side of the conduit distant from the point of entry. Similar results are obtained by by-passing a chosen portion of the conveying fluid, such as air, around the intake conduit, or by bleeding the vacuum line.

In the particular illustration of the invention selected in this case there has been illustrated an ash removing system but this is illustrative only and if a current is to be propelled by both suction and pressure the air fan, for example, would obviously be replaced by a liquid fan if the fluid were a liquid.

In the drawings:

Figure 1 is a diagrammatic view of the system. Figure 2 is a perspective view of the intake portion of the conveying conduit here shown as a pipe.

Figure 3 is a plan view of the entry pipe.

2 Figures 4, 5, 6 and 7 are cross sections respectively on lines 4—4, 5—5, 6—6, and 7—7 of Figure 3.

Figure 8 shows a modified form.

Figure 9 is a side elevation of the intake pipe of Figure 8.

Referring first to the diagrammatic view, Figure 1, 10 is a receptacle of any kind containing material to be transferred to a receiving receptacle 11, which could be a tank or the body of an ash removal truck. The intake pipe of Figure 2 is denoted as a whole by the numeral 14 and this pipe receives air under pressure thru pipe 15 from air pump 16, the suction end of which is connected thru pipe 17 with the top of the receptacle 11. Pipe 18, sometimes seventy feet or more in length, connects the intake pipe 14 with the clear space within receiving receptacle 11. Pipe 14 preferably has at least two openings therein and these are protected from above by shields 20 and 21 of any chosen shape. As the air pump 16 is started, a current of air passes thru the pipes 15, 18 and 17 and ashes in the receptacle 10 pass thru the openings protected in part by shields 20 and 21 and pass thru the pipe 18 to the receptacle 11 which may be of any convenient size, either mobile or not, as desired. Very frequently the tank mounted on the receiving truck is provided with a separator or filter 19 of any preferred form and the pipe 17 is in communication with the dust-free portion of receptacle 11 above the particle separator 19 so that there is constantly a suction not only in receptacle 11 but also in pipe 18 and obviously there is a pressure of appreciable amount in the pipe 15.

The particular form of the receiving receptacle 11 may be altered within wide limits. In the preferred form the filter 19 is at the entry side 40 and preferably at the highest point in the receptacle or tank. The pipe 18 opens centrally thru a solid baffle 59 which extends from side to side of the receptacle but is well short of the hopper-shaped bottom. The advantage of such a construction is that the pipe 18 discharges its air and particles in substantially a horizontal direction and the particles hit the far side 60 of the tank or truck body 11 and these particles then collect first at the bottom at the far side, as indicated by the numeral 61, while the air passes under the baffle 59 and thru the separator or filter 19 to the pipe 17.

Referring now to Figure 2, the pipe or duct 14 has a relatively small entry end 23 and a relatively large exit end 24. I prefer that the area

of the exit end 24 shall be at least double the cross sectional area of the entry end and that the area of the pipes 15 and 18 shall be about the same as the area of the exit end 24 and, therefore, about twice the area of the intake end thus giving an appreciable velocity at the initial end of the intake pipe. The pipe at its entry end 23 is preferably rectangular and preferably having a height of less than one-third its width but could readily be of other shape.

As seen in Figure 2, in which the adjusting plates are purposely omitted, the first entry hole 25 is just about half the width of the pipe and its entire rear portion is covered by the shield 20, the top of the shield being domed if desired but preferably of plan dimensions as the rear portion of the hole 25 and being elevated about twice the height of the height of the intake pipe at this point. At the rear the shield has a back panel 23 which merges with the top 30 of the intake pipe which at this point is of a height, on that side of the conduit, midway between the top of the shield 20 and the top 31 of the pipe. The second hole is numbered 32 and like the initial hole 25 is of half the width of the pipe. The shield 21 is quite similar to the shield 20 and like it has a rear panel 33 which joins the top 35 of the intake pipe so that beyond the shield 21 the intake pipe is rectangular being a bit wider than it is high.

If the pipe exactly as in Figure 2 were designed for a particular amount of fluid at a given rate of speed and a given volume of material to be carried, the initial edges of the holes 25 and 32 could be placed at such a distance from the initial edges of the shields that the flow would be exactly as desired. In practice, however, the intake margins must be adjusted with considerable care and I therefore provide, as best seen in Figure 3, a slide 40 for one of the intake entries and a similar slide 41 for the other entry. Each of the slides consists in a perfectly flat plate having a central slot 42 so that it can be secured in any adjusted position longitudinally of the pipe as for example by a set screw 43. The slides are mounted on the top surface 31 of the intake pipe and by moving either slide longitudinally so that it does not reach the shield or at the other extreme so that it extends quite well inside of the shield, the volume of flow into the holes 25 and 32 can be very accurately adjusted. A rather normal setting for say sixty feet of line would be that the far intake 32 should have its slide about $\frac{3}{4}$ inch inside of the shield 21 whereas the initial intake would have its slide edge about $\frac{1}{4}$ inch away from the initial portion of the shield. The best results are had when the exit portion 24 has a definite suction, the entry portion 23 a definite pressure, and these are balanced just beyond the rear wall 23 of shield 20, that is a bit in front of the initial edge of shield 21.

Considering that the material is flowing thru the pipe an arch would tend to form at a point in front of each of the entry holes 25 and 32. But since the current is deflected by the forming arches, the current naturally follows a sinuous curve denoted by the dashed arrows 50. This sinuous curve of air or liquid will erode each of the arches thus being formed by pulling away a portion of their supporting surfaces and the greater the building of the arch, the stronger the force tending to dislodge one or both of its supports; consequently while arches do tend to form, they are destroyed long before they have an appreciable effect on the flow of the ashes, finely

divided material, or solid objects being carried by the fluid stream.

In the somewhat modified form shown in Figure 8 the hopper 10a has a simpler intake pipe, the one shown having no adjustment. The pipe 14a is illustrated as having two openings but either of the two openings may be used alone. The initial opening 25a is formed by cutting the circular pipe 14a by a vertical cut such as 44 extending about half way of the pipe. A sloping cut such as 45 makes an angle with the vertical cut about as shown and then a flat sheet 46 is secured to the pipe to close the same in part, forming a Venturi opening below the sheet 46 and leaving the vertical segmental cut open for entry of the ashes. If a second opening is used, its vertical cut 48 is preferably less than half the diameter, consequently to have the two openings of equivalent size the upper portion of the pipe beyond the second opening is raised or hooded as at 50 so that the depth of the vertical opening is the same in the two cases.

In this modification the pressure line 15 and the vacuum line 18 are joined by a by-pass 51 having a valve 52 therein to close the by-pass or to open it to a desired degree. The bleeder valve 53 in line 18 may be opened in case the solids tend to enter in too great volume into the vacuum line. In such cases as the bleeder valve is opened less and less solids are taken from the hopper until the desired vacuum has been restored. This valve 53 may be opened by hand or may be automatic, opening as the vacuum pressure moves towards zero. It is sometimes convenient to have gages in the pressure and vacuum lines as indicated at 57 and 58 respectively. The by-pass may be used exactly as shown in connection with the preferred form of the intake duct which in turn might, if desired, have a single opening. In both forms there is under all conditions an open passage for the flow of air as air always tends to travel in the line of least resistance and the design of the duct is such that it is impossible for a mass of solids only to enter and block the conveying line because of necessity both air and solids are simultaneously fed.

If the by-pass 51 were omitted, as the vacuum pressure grew more and more negative a point would be reached where the air or other fluid passing thru the intake pipe would be insufficient to satisfy the needs of the vacuum line and hence too great a quantity of solids would be drawn in, chocking the pipe. With the by-pass, however, the extra air or fluid, unaccompanied by solids, would be available to carry the solids and to reduce the amount of the vacuum at the pit, that is at the point where the solids are picked up. While the bleeding (at the vent or bleeder valve 53 in line 18) would serve about the same purpose, it adds outside air and this must be removed by bleeding at the pressure manifold of the machine just on the pressure side of the fan 16. The by-pass and bleeder work well together or either can be used separately.

What I claim is:

1. An anti-arch intake including a substantially horizontal pipe having a plurality of openings in the top side thereof, said openings being spaced both laterally and longitudinally and a shield above to prevent material from falling vertically into the covered portion of the opening, while permitting the material to pass angularly into such portions of the openings as are covered by the shields.

2. The device of claim 1 in which an adjustable horizontal slide is movable with respect to each shield to alter the volume of material received in the opening by increasing or decreasing the area of the uncovered portion of the opening.

3. The device of claim 1 in which the openings each have a width of roughly one-half of the pipe and each opening and shield is entirely to one side of the longitudinal centerline of the pipe.

4. The device of claim 1 in which the pipe is rectangular in cross section, the holes are rectangular, the shields are channel-shaped, open at the front end above the opening and are each closed at its rear end.

5. The device of claim 1 in which the cross sectional area of the intake pipe at its exit end is at least double that at the entry end and each shield rises to a level higher than the top of the entry end and has an open front end through which material may pass angularly to the covered portion of the opening.

6. An intake pipe generally rectangular in cross-section and having near the edge at the junction of the top and one side an opening approximately half the width of the pipe and having a second entry hole approximately half the width of the pipe and extending from the opposite top edge of the pipe, a channel-shaped shield closed at its rear extending above a portion of each opening and having a flat top surface to prevent vertical entry of material into the pipe for such portion of the hole as is protected by the shield, a slide mounted on the top of the pipe adjacent each shield and movable to cover a selected portion of the hole not covered by the shield and upon further movement to extend into the shield.

7. An ash removal intake pipe for use in a system including an ash receptacle and a receiving receptacle connected by a pipe, an intake pipe within the first receptacle and communicating with the first mentioned pipe, means for withdrawing air from the receiving receptacle and for discharging air under pressure into the intake pipe; said intake pipe having a plurality of ash receiving openings in the top thereof, each of the openings being protected for a portion of its extent by a shield bridging a portion of the opening and open at its front to discharge ashes angularly into the opening and a slide moving into and out of the shield to control the area of each of the intake openings independently of the other openings.

8. An ash removal intake pipe to be placed within an ash hopper near the bottom thereof, said pipe having an opening in the top thereof, a shield having an ash supporting top positioned well

above a portion of the opening so as to leave a space thru which the ashes may pass by gravity into the pipe, a pressure pipe and the ashes may move angularly into the covered portion of the opening connecting with one end of the intake pipe and a vacuum pipe connected to the other end, and means connecting the pressure and vacuum pipes to form a closed circuit.

9. The device of claim 7 with a valved by-pass pipe connecting the pressure and vacuum sides of the intake pipe.

10. The device of claim 9 with a bleeder valve located downstream of the junction of the by-pass pipe and the intake pipe.

11. An intake pipe having a hooded opening and a V-cut opening spaced therefrom, the V-cut opening having a sloping side and a side normal to the pipe axis, the sloping side being covered by a flat sheet, whereby the sole entry to the pipe at the V-cut opening is thru the normal cut side of the opening.

12. The combination with a main ash removal pipe having a pressure end and a vacuum end and adjustable size ash receiving openings, of a by-pass pipe joining the main pipe in the pressure side upstream of the openings and in the vacuum side downstream of the openings, and a bleeder valve in the main pipe downstream of the junction with the by-pass pipe, whereby when ashes tend to enter the openings in too great volume, the bleeder valve may be opened so that less and less ashes are taken into the main pipe until the desired vacuum has been restored.

13. The combination of claim 12 with means to control the flow through the by-pass.

NEIL H. GEBHARDT.
